UNITED STATES PATENT OFFICE.

WILLIAM D. THOMPSON AND ALFRED R. WILSON, OF DETROIT, MICHIGAN, ASSIGNEES
TO HUTCHINS CAR ROOFING COMPANY, OF DETROIT, MICHIGAN, A CORPORATION OF
MICHIGAN.

CAR-ROOF.

1,323,336.

Specification of Letters Patent.

Patented Dec. 2, 1919.

Application filed September 17, 1915, Serial No. 51,275. Renewed September 3, 1918. Serial No. 252,470.

To all whom it may concern:

Be it known that we, WILLIAM D. THOMPSON and ALFRED R. WILSON, citizens of the United States of America, residing at Detroit, in the county of Wayne and State of Michigan, have invented certain new and useful Improvements in Car-Roofs, of which the following is a specification, reference being had therein to the accompanying drawings.

The invention relates to car roofs of the outside type, and it is the object of the invention to provide a thoroughly weather-proof light gage metallic covering for the board roof, and one which is composed of freely, independently-movable units, so as to provide flexibility.

In the drawings:—

Figure 1 is a cross section through the roof; and

Fig. 2 is a section longitudinally of the roof on line x—x Fig. 1.

Our improved construction is one designed particularly for use with the wooden frame and board cover type of car roofs, in which A are the side plates, B the car-lines extending between the same, C the ridge purlin and D the roof boards preferably formed of matched lumber and extending across the carlines and purlins.

The metallic cover is formed of a series of light gage roofing sheets E, which are provided with upstanding edge flanges F and down-turned eave flanges G having open inwardly-extending return-bends H. Intermediate these sheets are weather-proofing caps I embracing the upstanding flanges of said sheets, and said caps are secured by bolts I', preferably riveted to an embossed portion J and extending through an aperture K in the roofing boards. The inner end of each bolt has a nut L engaging the same, while an angle bracket M is secured to the side plate A and is apertured for engaging the bolt, the outer end of said bracket being bent down at N to form a lock for the nut L. O is a metallic strip extending longitudinally of the car and inserted between the roof boards and the plate A, said strip having the angle bent portion P which fits over the outer sheathing of the car, the outwardly-extending portion Q and downturned flange portion R, the latter engaging the open return-bend H. The caps I preferably have foot-flanges S bearing upon

marginal raised portions S' of said sheets. T are wooden strips which extend transversely of the roof preferably from eave to ridge being arranged between the upstanding flanges F of the adjacent sheets beneath the caps I. These strips T form stops for limiting the movement of the sheets, and also preferably from supporting bearings for the edges of the sheets. To this end the upstanding flanges F are provided with laterally extending edge portions F', which overlap and rest upon the strips T and sustain the load of the caps I when clamped down upon the portions S'. U is a fascia which is secured to the side of the car below the eave flanges of the roofing sheets and extends outward beyond the same, so as to form a protection against anything brushing along the side of the car. The ends of the caps are also downturned to overlap the downturned flanges of the sheets at S' and to lie adjacent thereto.

With the construction as described, the metallic covering is free to adjust itself to any flexing, weaving or distortion of the wooden frame and without any bending of the metal, as the roofing sheets are pivotally secured and relatively movable. Sufficient clearance space is provided between the caps I and the spacer strips T to permit of the maximum relative movement of the sheets, while the return-bent flanges H engaging the downturned flanges R on the strips O will limit the amount of relative movement. The pressure of the foot-flanges S and the caps I will hold the sheets down upon the board roof and will also press the lateral flanges F' into contact with the upper face of the strip T. The lateral flanges F' resting upon the upper face of the strip T will support the raised portions S' of the sheets normally in engagement with the foot flanges S of the caps. This is desirable since the roofing sheets are light gage and have not sufficient strength if their outer edges are not supported, to return their raised portions into engagement with the foot flanges of the cap when the raised portions are subjected to abnormal stresses. The present arrangement will produce an effective weather-proofing joint, while not interfering in any way with the free independent movement of the sheets.

What we claim as our invention is:—

1. A car roof, comprising a load-sustain-

ing board roof, and a light-gage metallic covering comprising a series of independently-movable sheets having upstanding and laterally-extending side flanges with a portion intermediate said upstanding flanges and the body of the sheet raised above the plane of the latter, caps embracing said upstanding flanges and bearing upon said raised portions of the sheets, and wooden strips intermediate said upstanding flanges forming supporting bearings for the laterally-extending portions thereof.

2. A car roof, comprising a load-sustaining board roof and a metallic covering comprising a series of independently-movable sheets, weather-proofing caps embracing upstanding flanges on said sheets, brackets secured to the side plates, bolts attached to said weather-proofing caps and extending through said brackets, and nuts engaging said bolts and locked in place by said brackets.

3. In a car roof, the roof sub-structure, a light gage metallic covering therefor and comprising a series of roofing sheets having the portion of the sheet adjacent to the side edge thereof raised above the plane of the body of the sheet, a cap spanning the joint between adjacent sheets and bearing upon said raised portions of the sheet at the joint, and means at the junction of adjacent sheets forming a support for the raised portions of the sheets adjacent to the outer edges of said raised portions.

35 4. In a car roof, the roof sub-structure, a light gage metallic covering therefor and comprising a series of roofing sheets having the portion of the sheet adjacent to the side edge thereof raised above the plane of the body of the sheet, a cap spanning the joint between adjacent sheets and having foot flanges bearing upon said raised portions of the sheet at the joint and a supporting bearing at the junction of adjacent sheets embraced by said cap, said sheets engaging said supporting bearing within the plane of the side edges of the cap.

5. In a car roof, the roof sub-structure, a light gage metallic covering therefor and comprising a series of roofing sheets having the portion of the sheet adjacent to the side edge thereof raised above the plane of the body of the latter, a cap spanning the joint between adjacent sheets and having foot

flanges bearing upon said raised portions of the sheet at the joint and a supporting bearing at the junction of adjacent sheets forming a spacer for said cap and acting to support the outer edges of said sheets.

6. In a car roof, the roof sub-structure a light gage metallic covering therefor and comprising a series of roofing sheets having upstanding and laterally-extending side flanges with a portion intermediate said upstanding flanges and the body of the sheet raised above the plane of the latter, a cap embracing said upstanding flanges and bearing upon said raised portions of the sheets, and a supporting bearing intermediate said upstanding flanges and supporting said laterally-extending portions thereof.

7. In a car roof, the roof sub-structure, a light gage metallic covering therefor and comprising a series of roofing sheets having the portion of the sheet adjacent to the side edge thereof raised above the plane of the body of the sheet, a cap spanning the joint between adjacent sheets and bearing upon said raised portions of the sheet at the joint, and means at the junction of adjacent sheets forming a support for the raised portions of the sheets adjacent to the outer edges of said raised portions, the sides of said support forming means and cap being sufficiently spaced apart to permit of limited lateral movement of said sheets.

8. In a car roof, the roof sub-structure, a light gage metallic covering therefor and comprising a series of relatively movable roofing sheets having upstanding and laterally-extending side flanges with a portion intermediate said upstanding flanges and the body of the sheet raised above the plane of the latter, a cap embracing said upstanding flanges and bearing upon said raised portions of the sheets, and a supporting bearing intermediate said upstanding flanges and supporting said laterally-extending portions thereof, said cap and supporting bearing being spaced sufficiently to permit of limited relative movement of the sheets.

In testimony whereof we affix our signatures in presence of two witnesses.

WILLIAM D. THOMPSON.
ALFRED R. WILSON.
